UNITED STATES PATENT OFFICE.

JAMES MACDONALD, OF CHICAGO, ILLINOIS.

LIFTING DEVICE.

1,223,410.

Specification of Letters Patent. Patented Apr. 24, 1917.

Application filed May 15, 1916. Serial No. 97,630.

To all whom it may concern:

Be it known that I, JAMES MACDONALD, a citizen of the United States, residing at Chicago, in the county of Cook and State of Illinois, have invented certain new and useful Improvements in Lifting Devices, of which the following is a description, reference being had to the accompanying drawings, forming a part of this specification, 10 in which corresponding numerals of reference in the different figures indicate like parts.

The object of my invention generally stated, is to provide a simple, cheap and effective lifting device adapted for the lifting of heavy loads where great power rather than speed is an essential; such, for example, as in the raising of forms used in concrete wall or other monolithic construction where 20 the use of jack screws or similar appliances are rendered impractical except at prohibitory expense. I accomplish said object by means of primary and secondary frame elements, combined with independent gripping 25 members adapted to grip a vertical supporting member such as a rod or bar, either suspended from above or rigidly supported from beneath, in such a way as to alternately grip and release said supporting 30 member so that a reversal of the lever by which they are actuated may serve to lift the entire device step by step together with its load, said device being so combined and actuated with reference to said vertical supporting member as to act concentrically 35 thereon so as to avoid any lateral distortion thereof, thereby insuring the upward movement of both lifting device and load in a vertical plane, all of which is hereinafter 40 more particularly described and definitely pointed out in the claims.

In the drawings

Figure 1, is a side elevation of my improved lifting device together with a vertical supporting rod and a form for concrete work bolted to said lifting device.

Fig. 2, is a rear view taken at right angles to that shown in Fig. 1.

Fig. 3, is a central longitudinal sectional view of said lifting device as it would appear in operative connection with a supporting rod.

Fig. 4, is a section in plan taken upon the line 4, Fig. 3.

55 Fig. 5, is a section in plan taken upon the line 5, Fig. 3.

Fig. 6, is a like view taken upon the line 6, Fig. 3, and

Fig. 7, is a side elevation of the machine as it would appear when not in use. 60

Referring to the drawings, 1 indicates generally an upright support or frame formed from cast metal having a body portion consisting of vertical supporting members 2, 2, spaced apart and rigidly attached 65 to or formed integral with a horizontal base portion having laterally extended flanges 3, 3, and a connecting web 4, Fig. 2.

The parts 2 are curved toward each other and merged at their upper ends into a guide 70 portion 5, the front of which is curved preferably into a half round form in cross-section as shown in Fig. 6, while the sides 6, 6, are arranged parallel to each other so as to provide an opening in the rear. 75

Interposed between the members 2, 2, is a secondary or auxiliary frame portion consisting in the example shown, of parallel plate-like members 7, 7, which are spaced apart and provided with enlarged concentric bores at their upper ends into which trunnions 8, 8, extending laterally in opposite directions from a bifurcated head 9, are journaled. In addition to said trunnions 8 are secondary trunnions or bosses 10, 10, 80 which in the example shown are illustrated as parts of a single shaft cut away at 11, Figs. 3 and 5, for the purpose hereinafter stated. The secondary trunnions 10, are in eccentric relation to the trunnions 8, as best 85 shown in Figs. 3 and 5, and they with the head form a pivoted connection between the primary and secondary frames. The head 9 is provided with a rear extension 12 having a socket 13 therein for the reception of a 90 lever arm 14. It will be understood from what has been stated that the members 7 which I have termed the secondary frame, 95 are suspended from the eccentric head 9, so that one frame may be caused to have a slight up and down movement with respect to the other when the head is oscillated by the movement of the lever-arm 14. Depending portions 15, 15, at the lower ends of the parts 7, Figs. 2 and 3, are provided with vertical notches 16 for the reception of guide-lugs 17 rigidly attached to the web 4, to guide the members 7 in their up and down movement. Counterpart cam members 18, 18, better shown in Figs. 3 and 4, are provided with trunnions 19, which are journaled 105 in a common horizontal plane in the mem-

100

bers 7. Each of said cam-members is provided with an eccentric serrated gripping jaw or cam 20, the opposing serrated faces 21 of which are spaced apart or separated from each other a predetermined distance to provide for the insertion between them of a rod or bar 22, which they are adapted to grip in the manner and for the purpose hereinafter described. Arms 23 are formed 10 upon or rigidly attached to the members 18 and extended in opposite directions therefrom as shown, said arms being preferably limited in their upward movement by means of guards 24, attached in any approved way 15 to the main frame.

A lever arm 25, is provided with trunnions 26, which are pivoted in lugs 27, extending rearwardly from the parts 6. Said lever is provided upon its forward end with 20 a serrated gripping jaw 28, adapted to grip the rod or bar 22 when the free end of the lever is pressed downwardly so as to suspend the frame from said rod and prevent the downward movement of said frame. A 25 bore 29, Fig. 3, is formed in the web 4, and serves as a guide to aid in holding said rod in concentric relation to the frame.

The laterally extended base plates 3, are provided with bores 30, Fig. 4, for the reception 30 of bolts 31, Figs. 1 and 2, adapted to be extended downwardly through any suitable beams or other members 32, for the suspension therefrom of the usual concrete form 33.

The operation of the device for the purpose specified is as follows: In ordinary concrete construction work the form 33, of predetermined height, preferably about three or four feet, is placed upon the ground in position to receive the concrete filling. In 40 the example illustrated a section of a straight wall is indicated but it is manifest that the form may be varied to adapt it to the character of the structure involved. It is essential that the entire form or forms 45 should be so lifted as to be kept substantially level and in a vertical plane, thereby requiring approximate uniformity of action throughout the entire length. In order to insure such action a considerable number of 50 lifting machines may and usually would, be required, the number being proportionate to the relative weight of the forms and the character and extent of the structure to be erected. A supporting rod 22, would, therefore, be required for each machine and these 55 should be placed sufficiently near to each other to enable the form to be lifted without distortion. The machines being positioned and rigidly bolted to the form as described, 60 the rods 22, are projected downwardly through the body of the device and form in the manner shown until their lower ends rest upon a solid foundation. Said rods are located in a vertical plane preferably mid-way 65 between the walls of the form as shown

in Fig. 2. A filling of concrete 34, is then placed in the form and allowed to remain long enough to insure an initial set. When it is desired to lift the form, the lever 25 of the first machine in the series is depressed so 70 that the holding cam 28, shall be caused to have a firm grip upon the rod 22. The lever 14 is then raised to the position shown in Fig. 3, thereby lifting the parts 7, and with them the pivoted members 18, and in turn causing the serrated cams 20, to slide upwardly upon and in contact with the rod 22, diametrically opposite to each other. When the lever 14 is raised to its full height the arms 23 are brought into contact with the 75 guards 24 with sufficient force to cause the cams 20 to firmly grip the rod. Thereupon the lever 14 is depressed, whereupon the trunnions 8, acting as a fulcrum for the lever, cause the trunnions 10 to be lifted, thus carrying with them the frame 1 and with it the form, which movement is permitted by the gripping of the cams 20 upon the suspending rod, thereby serving as a rigid support for the members 7, and the simultaneous 80 slipping upon said rod of the auxiliary holding cam 28. It will thus be seen that the frames are always caused to move in opposite directions with respect to each other by alternately climbing or ascending the supporting rod step-by-step, one being stationary while the other is advanced. 85

While the lifting device is intended to be actuated by hand, it is essential that it should be capable of exerting great power. 100 This is rendered possible in view of the slight upward movement of the form required, usually about one fourth of an inch with each depression of the lever. When a number of machines are employed upon a given form they should be actuated either in unison or in successive order, the latter being preferable as requiring but one attendant. In this way the form may be elevated as rapidly as it is possible to supply the material and allow it to harden. 105

It is immaterial how the suspending rod 22, is supported whether from top or bottom, so long as it is caused to bear a fixed relation to the concrete structure so that the 110 form may always be lifted in a vertical plane. 115

One of the important advantages of the device is that the lifting force exerted thereby is always concentric with the axis of the suspending rod. Inasmuch as the latter passes through the bore in the web 4, it is always maintained at the base in fixed relation to the walls of the form and hence the latter is forced to be continuously moved in 120 a vertical plane. 125

I do not wish to be limited to the exact construction shown inasmuch as it may be varied without departing from the spirit of the invention; nor do I intend to be limited 130

to the specific application described, it being obvious that it may be utilized for the lifting of any load wherein speed of movement is not required, provided it is practical 5 to supply a suspending rod for it to act upon.

Having thus described my invention, I claim—

1. A device for moving a concrete form in a plane parallel to that of a stationary 10 rod to which said device is adapted to be movably connected, comprising, in combination, primary and secondary frame members, the former of which is in direct operative connection with the form to be advanced, an oscillatory head having opposing 15 trunnions thereon journaled respectively in said primary and secondary frames, the latter being in the plane of the axis of the rod to which said device is movably connected, 20 a lever fulcrumed upon said second named trunnions, and gripping means upon each of said frames arranged to be in concentric operative relation to said rod for alternately gripping the same against movement in one 25 direction while free to slide in the reverse direction.

2. A device for elevating a concrete form in a vertical plane by climbing an upright sustaining rod, comprising primary and secondary 30 frame members, the former of which is in operative connection with the form, an oscillatory head having complementary trunnions thereon, one pair of trunnions being journaled in said primary frame in the 35 plane of the axis of such sustaining rod and

the other in said secondary frame, a lever fulcrumed upon said first named trunnions, and gripping means upon each of said frames in concentric relation to said rod for gripping the same against the gravitating 40 action of the load while free to be alternately released and to slide upwardly thereon when said lever is vibrated.

3. A device for elevating a concrete form in a vertical plane by climbing an upright 45 sustaining rod, comprising primary and secondary frame members, the former of which is in direct operative connection with the form to be lifted, an oscillatory head having complementary trunnions thereon journaled 50 respectively in said primary and secondary frames, the former being in the plane of the axis of the sustaining rod, a lever fulcrumed upon said first named trunnions, complementary gripping members upon said secondary 55 frame located upon opposite sides of said sustaining rod to normally sustain the load in concentric relation thereto, and gripping means upon said secondary frame in concentric relation to said rod for sustaining the load when said complementary gripping members are released.

In testimony whereof, I have signed this specification in the presence of two subscribing witnesses, this 12th day of May, 1916. 65

JAMES MACDONALD.
